UNITED STATES PATENT OFFICE.

REEVA HUSON LORIMER, OF BOSTON, MASSACHUSETTS.

CUP-CLASP.

1,258,792.

Specification of Letters Patent. Patented Mar. 12, 1918.

Application filed September 22, 1917. Serial No. 192,692.

To all whom it may concern:

Be it known that I, REEVA H. LORIMER, a citizen of the United States, residing at Boston, in the county of Suffolk and State 5 of Massachusetts, have invented new and useful Improvements in Cup-Clasps, of which the following is a specification.

This invention relates to a plate-engaging cup clasp or holder supporting a cup on a 10 plate so that the plate and cup may be conveniently held by one hand of the user, the cup being supported in such manner that while it may be readily raised from the plate by the other hand of the user, it is confined 15 against lateral displacement relatively to the plate.

The invention is embodied in certain improvements in a plate-engaging cup clasp or holder, hereinafter described and claimed.

20 Of the accompanying drawings forming a part of the specification—

Figure 1 is a perspective view of a cup clasp embodying the invention.

Fig. 2 is a side elevation of the clasp and 25 of a cup supported and confined thereby, and an edge view, partly in section, of a plate with which the clasp is engaged.

The same reference characters indicate the same parts in all the figures.

30 My improved cup clasp is preferably constructed entirely of wire, which may be plated or otherwise ornamentally surfaced, and, in the embodiment of the invention here shown, includes an endless sinuous wire 35 body, the sinuosities of which form not only a plurality of wings designated by 12, 12 and 13, and composed of arched portions of the wire, said wings being formed and relatively arranged to support and prevent lateral displacement of a cup, while permitting 40 the latter to be freely raised, but also a plurality of feet designated by 14, 15, 15 adapted to bear on different portions of the upper surface of a plate, and formed by inverted arched portions of the body. The 45 clasp also includes a resilient wire jaw 16 attached at its ends to the body and adapted to bear yieldingly on the under side of the plate.

50 The wings 12 which I call the side wings are formed and arranged to bear on substantially opposite portions of the cup and prevent lateral displacement thereof in the direction indicated by the arrow α . The wing 55 13, which I call the stop wing, is formed and arranged to bear on an intermediate portion

of the cup and prevent lateral displacement thereof in the direction indicated by the arrow γ .

The foot 14 is formed and arranged to bear on the upper surface of the rim portion of the plate, and the feet 15, which are spaced apart, are formed and arranged to bear on the upper surface of the bottom or body of the plate. The device is therefore a tripod adapted to bear on a plate at three spaced apart points and be firmly supported by the plate.

The jaw 16 is formed from a length of wire soldered or otherwise attached at its 70 ends to the wings 12 and bent to form necks 16^a extending across the margin of the plate, the intermediate portion of the jaw projecting inwardly under the foot 14, and coöperating therewith in yieldingly grasping a 75 portion of the plate. The resilience of the jaw 16 is such that it is adapted to conform to plates of different shapes and thickness.

The portions of the wings 12 which are connected by the foot 14 are spaced apart to 80 enable the handle of the cup to project between said wings.

The clasp is preferably provided with 85 holders for concomitant articles such as a spoon, a fork, and a lump of sugar. As here shown I provide three holders, two of which are formed by portions of the wings 12 and by supplemental wings 18 composed of lengths of wire having bent end portions soldered or otherwise attached to the wings 90 12, one of these holders being adapted to support a spoon S, and the other a fork. The third holder is formed by a portion of the wing 13 and by a supplemental wing 19 composed of a length of wire soldered or 95 otherwise attached to the wing 13, and constituting a shelf adapted to support a lump of sugar L. The side portions of the wing 13 may be connected by a wire cross bar 20 constituting a part of said shelf and tying 100 together the said side portions.

I claim:

1. A cup clasp comprising a body having two side wings formed to bear on substantially opposite portions of a cup, a stop wing formed to bear on an intermediate portion of the cup, said wings being arranged to support the cup and prevent lateral displacement thereof in any direction, an outer foot located between the two side wings and formed to bear on the upper surface of a plate rim, and a pair of spaced apart inner

feet projecting below the outer foot and located between the side wings and the intermediate wing, said inner feet being formed to bear on the upper surface of the plate bottom, and a resilient jaw attached to the side wings and arranged to coöperate with the outer foot in yieldingly grasping the plate rim.

2. A cup clasp comprising an endless sinusous wire body, the sinuosities of which constitute two side wings formed to bear on substantially opposite portions of a cup, a stop wing formed to bear on an intermediate portion of a cup, an outer foot located between the two side wings and formed to bear on the upper surface of a plate rim, and a pair of spaced apart inner feet located between the side wings and the intermediate

wing and extended below the outer foot to bear on the upper surface of a plate bottom, and a resilient bent wire jaw attached at its ends to the side wings and adapted to bear yieldingly on the under surface of that portion of the plate on which the outer foot bears.

3. A cup clasp as specified by claim 2, the upper portions of the sinuosities forming the side wings being provided with supplemental wire wings having bent end portions united to the side wings, said supplemental wings and bent end portions coöperating with the upper portions of the side wings in forming holders for concomitant articles.

In testimony whereof I have affixed my signature.

REEVA HUSON LORIMER.
